UNITED STATES PATENT OFFICE

167,671

HOLDER FOR MILK CONTAINERS

Joseph V. Biggs, Decatur, Ill.

Application September 7, 1951, Serial No. 16,576

Term of patent 3½ years

(Cl. D44—10)

To all whom it may concern:

Be it known that I, Joseph V. Biggs, residing at Decatur, State of Illinois, have invented a new, original, and ornamental Design for a Holder for Milk Containers, of which the following is a specification, reference being had to the accompanying drawings, forming a part hereof.

Fig. 1 is a side elevational view of a holder for milk containers, showing my new design.

Fig. 2 is a rear elevational view.

Fig. 3 is a top plan view, and,

Fig. 4 is a perspective view thereof.

I claim:

The ornamental design for a holder for milk containers, as shown.

JOSEPH V. BIGGS.
